UNITED STATES PATENT OFFICE.

ANDRÉ JULES MICHELIN, OF PARIS, FRANCE.

DESIGN FOR A TIRE.

Application filed January 6, 1927. Serial No. 20,291. Term of patent 14 years.

To all whom it may concern:

Be it known that I, ANDRÉ JULES MICHELIN, a citizen of France, residing at Paris, France, have invented a new, original, and ornamental Design for Tire, of which the following is a specification, reference being had to the accompanying drawings, forming a part thereof.

Figure 1 is a plan view of a portion of a tire, and

Figure 2 is a fragmentary section on the line 2—2 of Figure 1.

I claim:

The ornamental design for a tire as shown. In testimony whereof I affix my signature.

ANDRÉ JULES MICHELIN.
